US00D961557S

(12) **United States Design Patent** (10) **Patent No.:** **US D961,557 S**
(45) **Date of Patent:** **** Aug. 23, 2022**

(54) **EARPHONE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, Vienna (AT); **Clement Tissandier**, San Francisco, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/804,821**

(22) Filed: **Aug. 23, 2021**

Related U.S. Application Data

(63) Continuation of application No. 29/764,724, filed on Dec. 31, 2020, now Pat. No. Des. 928,745, which is a continuation of application No. 29/741,273, filed on Jul. 10, 2020, now Pat. No. Des. 907,010, which is a continuation of application No. 29/705,727, filed on

Sep. 13, 2019, now Pat. No. Des. 906,297, application No. 29/804,821, filed on Aug. 23, 2021, which is a continuation of application No. 29/741,272, filed on Jul. 10, 2020, now Pat. No. Des. 929,374, which is a continuation of application No. 29/705,727, application No. 29/804,821, filed on Aug. 23, 2021, which is a continuation of application No. 29/741,274, filed on Jul. 10, 2020, now Pat. No. Des. 928,743, which is a continuation of application No. 29/705,727.

CLAIM

The ornamental design for an earphone, as shown and described.

DESCRIPTION

FIG. 1 is a front perspective view of an earphone showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the earphone that form no part of the claimed design.

1 Claim, 4 Drawing Sheets

FIG. 1**FIG. 2**

FIG. 7

FIG. 8
